[57] CLAIM

The ornamental design for a scouring pad holder, as shown and described.

DESCRIPTION

FIG. 1 is an isometric view of my new scouring pad holder; FIG. 2 is a top view thereof;

FIG. 3 is a bottom view thereof;

FIG. 4 is a side elevational view thereof, the opposite side being identical;

FIG. 5 is a front elevational view thereof;

FIG. 6 is a rear elevational view thereof;

FIG. 7 is an isometric view of an alternative embodiment of my new scouring pad holder; and,

FIG. 8 is an isometric view of my new scouring pad holder illustrating, in phantom, a scouring pad engaged with my scouring pad holder.

The broken lines showing the scouring pad in FIG. 8 are for illustrative purposes only and form no part of the claimed design.
